UNITED STATES PATENT OFFICE

MONES GROSS, OF NEW YORK, N. Y.

BELT END ATTACHMENT

Original application filed April 14, 1930, Serial No. 343,160. Divided and this application filed July 11, 1930. Serial No. 467,320.

The present invention relates to strap or belt end reinforcements and is a divisional application from my allowed application, Serial No. 343,160 allowed April 14, 1930.

5. In my allowed application herein referred to an improved adjustable fastener for belts is disclosed, wherein the appearance of the belt is improved thru concealing the free end of the belt and also the butt end reinforcement.

10. It is the primary object of the present invention to provide an improved reinforcement for the butt ends of belts which will dispense with riveting, stapling or other fastening elements for attachment of the reinforcing head piece.

15. A further object of the invention is to provide a reinforcing head piece or cap for butt ends of belts which may be economically constructed from sheet metal stampings and of a construction to permit detachable coupling of a belt buckle in an efficient manner to the butt end of the belt.

20. Other objects and advantages of the invention will be apparent during the course of the following detailed description, taken in connection with the accompanying drawing forming a part of this specification and in which drawing:

25. Figure 1 is a central longitudinal section thru the connected ends of a belt provided with the improved reinforcing head piece.

30. Figure 2 is a front plan view showing portions of the buckle and belt broken away for 35. more clearly illustrating the manner of attaching the head piece to the belt end.

35. Figure 3 is a plan view of the blank from which the reinforcing head piece or cap may be formed.

40. Referring to the drawing in detail, and wherein similar reference characters designate corresponding parts thruout the several views, the letter A designates a flexible belt formed of leather or any other suitable material having its ends adjustably connected by the buckle B having detachable connection with the belt end reinforcing attachment or head piece C. The belt A has the butt or head end 4 and the loose or free end 5, the head piece C being applied to the butt

end 4 for detachably receiving the buckle B adjustably receiving the free end 5.

45. The buckle B includes the longitudinally arcuated face plate 6 and a clamp plate 7 extending in overlying relation at the inner side of the face plate and having its reduced end portion 8 bent substantially at a right angle toward the face plate 6 for providing a tongue 10 yieldably engaging the rear surface of the face plate inwardly of the forward edge 11 of the face plate.

50. A pivotally mounted keeper 12 serves to clamp the free end 5 of the belt against the inner side of the clamp plate 7 to prevent the free end from being withdrawn from its adjusted position with the buckle. The free belt end 5 as will be observed extends at the inner side of the butt end 4 and is concealed thereby.

55. Referring now to the reinforcing head piece or cap C for clamping engagement over the butt end 4 of the belt in a manner to be entirely concealed from view by the buckle face plate 6, the same is preferably formed from a sheet metal stamping shown in blank form in Figure 3.

60. The sheet metal head piece C is bent along the lines 14 and 15 shown in Figure 3 to provide parallel spaced apart inner and outer plates 16 and 18 respectively connected by the end plate 19. These plates 16, 18 and 19 form a channel-shaped cap adapted to be clamped over the terminal of the butt belt end 4 with the plates 16 and 18 respectively overlying the inner and outer surfaces of the belt end. The outer plate 18 is relatively narrow and is intended to overlie but a small portion of the outer surface of the belt from the end edge of the butt end 4. The inner plate 16 is of considerably greater length than the outer plate 18 and extends for a substantial distance over the inner surface of the belt.

65. The butt end of the belt is provided with a transverse slot 20 which extends parallel to the end edge of the butt end with its ends spaced an even distance from the upper and lower edges of the belt. This slot 20 forms an opening for receiving the buckle tongue 10 whereby the buckle may be detachably 70

coupled to the butt end of the belt with the butt end overlying the inner surface of the buckle face plate 6 and the slot fully closed at its outer side by the face plate.

Formed along the free side edge of the outer plate 18 is an elongated, rectangular-shaped tongue 22 of a length equal to the length of the slot 20 and of a width substantially equal to one-half the thickness of the belt. This tongue 22 is intended to be bent inwardly into the slot 20 over the forward edge of the slot.

The inner plate 16 has struck from its intermediate portion an elongated rectangular-shaped tongue 24 of a length equal to the length of the slot 20 and of a width substantially equal to one-half the thickness of the belt. This inner plate tongue 24 is spaced an equal distance from the bending line 14 as the spacing of the outer plate tongue 22 from the bending line 15 and is intended to be bent outwardly into the slot 20 over the forward edge of the slot with its end edge abutting with the end edge of the tongue 22 as clearly shown in Figure 1. Thus it will be seen that the tongues 22 and 24 aside from clamping the channeled portion of the head piece to the belt end also provide a metal reinforcing plate along the forward edge of the slot 20 against which the buckle tongue 10 pulls.

Projecting from the upper and lower marginal portions of the inner plate 16, rearwardly of the tongue 24 are attaching extensions or prongs 30 which are preferably of triangular or pointed shape as shown and these prongs 30 are intended to be bent into spaced overlying relation at the outer side of the plate 16 for biting into the belt along its upper and lower edges substantially midway between the inner and outer surfaces of the belt at a location inwardly of the slot 20. It may here be well to state that the head piece C is of a height equal to the width of the belt so that its upper and lower edges extend flush with the upper and lower edges of the belt. Thus the prongs 30 serve to anchor the rear end portion of the inner plate firmly to the belt at a location spaced inwardly of the slot 20 and relieve strain upon the belt material beyond the slot. The reinforcing head piece or cap C forms a metallic shield over the terminal of the butt end 4 and so reinforces the butt end of the belt as to prevent likelihood of the tongue 10 severing a portion of the belt beyond the slot 20.

Thus it will be seen that the head piece is firmly attached in a reinforcing relation to the butt end of the belt in a concealed position and without requiring fastening elements such as rivets, staples or the like. It is to be understood that any suitable number of the attaching extensions or prongs 30 may be provided along the upper and lower edges of the inner plate 16 for biting engagement

with the upper and lower edges of the belt material.

From the foregoing description it will be apparent that a novel belt end reinforcing head piece or cap has been disclosed which may be applied in a concealed reinforcing relation to the butt end of a belt or other similar strap.

Changes in detail may be made to the form of invention herein shown and described, without departing from the spirit of the invention or the scope of the following claims.

I claim:

1. In a belt end attachment, the combination with a belt having a buckle attaching opening at its butt end, of a reinforcing cap piece including plates clamped over the belt end, and a tongue bent into the buckle attaching opening from each of said plates and forming a wear plate along the forward edge of the opening.

2. In combination with a belt end having a transverse slot, a reinforcing cap piece including inner and outer plates clamped over the belt end, and a tongue bent into the slot from each plate in overlying relation to the forward edge of the slot.

3. In combination with a belt end having a transverse slot, a reinforcing cap piece including inner and outer plates clamped over the belt end, a tongue bent into the slot from each plate in overlying relation to the forward edge of the slot and means for attaching one of the plates to the belt inwardly of said slot.

4. In a reinforcement for belt ends provided with a transverse slot, a cap piece including inner and outer plate sections clamped over the belt end, said plates each having an elongated tongue bent into the slot along the forward edge of the slot, and attaching prongs provided at the upper and lower edges of the inner plate for engaging in the upper and lower edges of the belt inwardly of the slot.

5. In a reinforcement for belt ends provided with a transverse slot, a cap piece including inner and outer plate sections clamped over the belt end, said inner plate section extending beyond the slot, a tongue provided on each plate section for bending into the slot along the forward edge thereof, and prongs provided at the upper and lower edges of the inner plate section for biting into the belt material inwardly of the slot.

6. In a reinforcement for belt ends provided with a transverse slot, a cap piece including inner and outer plates clamped over the belt end, said inner plate extending beyond the slot, a tongue formed along the outer edge of the front section for bending into the slot, a tongue formed in the rear plate for bending into the slot, and pointed projections formed at the upper and lower edges of the inner plate for biting engage-

ment in the upper and lower edges of the belt end inwardly of the slot.

7. In a reinforcement for belt ends provided with a transverse slot, a cap including inner and outer plates, said inner plate projecting beyond the slot, a tongue formed on one edge of the front plate, a tongue formed in the inner plate, said tongues each being of a width equal to half the thickness of the belt strap end and adapted to be bent into edge abutting relation along the forward edge of the slot, and projections provided at the upper and lower edges of the inner plate inwardly of the tongue provided therein for biting into the belt material inwardly of the slot.

8. In a reinforcement for belt ends provided with a transverse slot, a cap piece clamped over the belt end to provide inner and outer plates, said inner plate being of a length to project beyond the slot, a tongue formed on one edge of the front plate for bending into the slot, a tongue struck from the intermediate portion of the inner plate for bending into the slot, and attaching prongs provided on the inner plate inwardly of its tongue for engaging the belt inwardly of the slot.

9. In a reinforcing cap piece for belt ends provided with a transverse slot, a plate clamped over the end of the belt to provide inner and outer plate sections, said inner plate section projecting beyond the slot, a tongue formed on one edge of the outer plate section and a second tongue formed in the inner plate section for bending into said slot along its forward edge, and a triangular-shaped projection provided on the upper and lower edges of the inner plate section inwardly of said tongue for biting into the belt material inwardly of the slot.

10. In a reinforcing cap piece for belt ends provided with a transverse slot, a plate clamped over the end of the belt to provide inner and outer plate sections, said inner plate section projecting beyond the slot, a tongue formed on one edge of the outer plate section and a second tongue formed in the inner plate section for bending into said slot along its forward edge, and a pointed prong provided at the upper and lower edges of the inner plate inwardly of the tongue for biting into the upper and lower edges of the belt material midway between the inner and outer faces of the belt.

11. A belt end attachment comprising a sheet metal blank bent to provide parallel spaced apart inner and outer clamp plates, said inner clamp plate being of greater length than the outer clamp plate, an elongated tongue formed along a portion of the free edge of the outer plate, an elongated tongue struck from the medial portion of the inner plate, said tongues having a combined width equal to the spacing between the clamp

plates, and a triangular-shaped prong provided at the upper and lower edges of the inner plate between its tongue and the free edge of the inner plate.
